TELEGRAMMING INSTRUMENT

DRAFTING INSTRUMENT

Theodore G. Alteneder, Melrose Park, Ill.
Application June 26, 1931, Serial No. 547,079

Claims. (Cl. 33-

Fig. 3 represents a horizontal section partially

This invention relates to drafting instruments and particularly to drafting instruments of the bow-type.

5 Bow instruments as usually constructed comprise a pair of legs attached to a handle and so arranged that the legs are resiliently urged apart toward the widest setting of the instrument. The outward urge of the legs is restricted and controlled usually by a threaded shaft pivotally
10 mounted in one leg and slidably mounted in the other and provided with a rotatable threaded nut arranged to bear against the outer side of the leg through which the threaded shank slides. Such prior art bow instruments have possessed certain disadvantages which may be summarized as: lack of firm support for the threaded shaft,

as, lack of firm support of the threaded nut which militates against free spinning of the threaded nut in making quick adjustments of the instrument when the legs are manually gripped and squeezed together to relieve the nut of frictional engagement with the leg, undue wear on the threads of the shaft through lateral friction due to misalignment, and excessive friction due to lateral movement of the nut and the adjacent leg.

25 It is among the objects of this invention, to provide a drafting instrument which obviates the disadvantages of the prior constructions, to pro-

disadvantages of the prior constructions, to provide a drafting instrument in which the threaded shaft joining the legs of the instrument is always held in such braced position as to facilitate free spinning of the threaded nut thereon; to provide a heavy compass of such construction

to provide a bow compass of such construction as to enable the use of a relatively high pitched thread for speedy adjustments; to provide a drafting instrument having a pair of legs with means to secure proper and accurate adjustments of the legs with a minimum of friction regardless substantially of slight irregularities in

40 alignment of the legs; to provide a drafting instrument with self aligning bearings; to provide a drafting instrument having a pair of legs with means rigidly engaging the legs for adjustment purposes. The foregoing and other objects are attained in the purely illustrative form of the invention disclosed in the accompanying drawing.

Referring to the drawing:

Fig. 1 represents a side elevation of a drafting instrument constructed according to the invention herein,

Fig. 2 represents a fragmentary enlarged vertical section partially in full lines through the adjusting mechanism and a portion of each of the spaced legs, and

Fig. 3 represents a horizontal section partially in full lines of the adjusting mechanism.

The instrument is preferably provided with a handle 10 to which legs 11 and 12 are connected in any desired manner. The legs 11 and 12 are preferably resilient so as to have an equal and opposite urge away from each other and from the axis of handle 10. As is well known in the art this may be accomplished by having rigid legs actuated by a suitable spring device (not shown) or by providing legs 11 and 12 of resilient material to form the spring bow-instrument disclosed in Fig. 1. Although the ends of the instrument legs may carry any desired terminals, for illustrative purposes leg 11 carries the adjustable lead 13, while leg 12 carries the adjustable needle point 14.

Leg 11 preferably has an enlargement 15 in which is a transverse horizontal cylindrical bore 16. Enlargement 15 has a vertical slot 17 communicating with the bore and on the inner surface of the leg is provided with a slot 18 communicating with bore 16. As shown in Fig. 2 the upper and lower surfaces of the respective slots 17 and 18 are flared outwardly from the bore 16 to effect clearance for the swinging shaft to be described. Leg 12 is similarly provided with a horizontal cylindrical bore 20 and an outwardly directed and upwardly and outwardly flared vertical slot 21 communicating with the bore 20, and with an inwardly directed flared vertical slot 22 also communicating with the bore 20. As will be noted these slots 21 and 22 and bore 20 are preferably formed in leg 12 in an enlargement 19 thereof.

A shaft 23 having the high pitch or quick threads 24 cut thereon, is of a diameter slightly but appreciably less than the width of slots 17 and 18 of leg 11 and slots 21 and 22 of leg 12. A cylindrical barrel 25 having a slideable and rotatable engagement in the bore 16 of leg 11 has a transverse bore 26 of a diameter to receive the fixed end of shaft 23 after it is disposed in registry therewith through slot 18 of the leg 11. The shaft 23 is anchored in the barrel 25 in any suitable manner as by the axial pin 27 disposed in a suitable bore of barrel 25 and passing through a registering bore in the end of shaft 23. It will be observed, and it is a feature of importance, that barrel 25 and shaft 23 as a unit may have a horizontal movement relative to the leg 11 limited only by the width of the slots 17 and 18 and may have an oscillation about the horizontal axis of the barrel 25 limited only by the upper and lower boundaries of slots 17 and 18.

A cylindrical bearing 28 having a transverse diametric bore 30 of such diameter as to slidably receive the threaded end of shaft 23, has a counter-sunk surface 31 toward the outer side of leg 12. The clearance of the transverse bore 30 of bearing 28, relative to the threads of shaft 23, is so slight as to be inappreciable except to prevent actual frictional engagement and wear on said threads. It will be observed that bearing 28 is free to rotate in the bore 20 and also to have axial horizontal sliding movement therein.

An adjusting nut 32, preferably provided with a milled peripheral edge 33, may be threaded upon the threads 24 of shaft 23 and is preferably 15 provided with a reduced axial prolongation or hub 34 having the curved edge 35 of such curvature as to sink within the counter-sink and engage upon the counter-sunk surface 31 of the bore 30 of the bearing 28. In this connection it 20 might be observed that the counter-sink 31 is elliptical in contour owing to its formation in the side of the cylinder but is adequate to form a rigid engagement of the adjusting nut with the slideable bearing 28. It will be observed that the lateral flare of the slot 21 in leg 12 is such as to 25 provide adequate clearance for the hub 34 to allow lateral movement of the shaft bearing 28 and adjusting nut 32 as a unit. It will also be observed that such permissible lateral movement 30 has no adverse effect on the setting of the legs.

To secure quick adjustments the operator may manually engage and squeeze the legs toward each other with the immediate effect of withdrawing the adjusting screw hub 34 from its engagement with the counter-sink 31 of the barrel 28. Whereas in ordinary prior constructions the shaft 23 has thereafter been free to swing up and down vertically in an elongated slot in leg 12 which has resulted in such absence of firm 40 support for the shaft as to militate against free spinning of the adjusting nut 32, it will be observed that the shaft 23 is guided and firmly supported by its engagement in the bearing 28 so that free spinning of the adjusting screw is 45 facilitated. Whereas in prior art constructions the anchored end of shaft 23 has been incapable of horizontal adjustment and it has sometimes occurred that the shaft 23, swingable in a fixed vertical plane, has been out of registry with the 50 appropriate slots in the cooperating leg so as to cause a lateral binding action on the shaft, accompanied by distortion when the adjusting nut was tightened, it is to be observed that owing to the facility with which either or both the cylindrical barrel 25 and the cylindrical bearing 28 may move axially of the bores in which they rotate, minor misalignments of the slots 17 and 18 of leg 11 relative to the slots 21 and 22 of leg 12 are immediately compensated for by self 55 alignment of either or both of the rotatable elements in their respective bores. It will be observed also that as the threaded adjusting nut

32 has a certain definite coaxial relation to shaft 23 and as the diametric bore 30 of the adjustable bearing 28 has a guiding sliding engagement with shaft 23, the bearing 28 is always properly disposed, regardless of the closeness or remoteness of the legs, as to cause proper guiding interengagement of the curved end 35 of hub 34 in the counter-sink 31.

As noted the invention is susceptible to various changes and modifications all of which are 10 to be construed as within the scope of the invention unless otherwise limited in the appended claims.

I claim:

1. In an instrument, a pair of legs, each leg 15 having a transverse bore and slots communicating therewith, a shaft of smaller diameter than the width of said slots, means for pivoting the shaft in the bore of one leg while permitting lateral movement of said pivot, and means for guiding the shaft in the bore of the other leg while permitting lateral movement of the shaft in the bore.

2. In a drafting instrument, a pair of legs, a threaded shaft, one of said legs having a guiding slot to slidably receive the threaded shaft, means for pivotally mounting the shaft on the other leg, said means being arranged for transverse sliding movement relative to said last mentioned other leg to permit registration of said shaft with the guiding slot in the first mentioned leg.

3. In a drafting instrument, a pair of legs, a threaded shaft, one of said legs having a guiding slot to slidably receive the threaded shaft, a slot 35 being formed in the other leg of greater width than the diameter of said shaft, said other leg having a transverse bore communicating with the slot, a barrel slidably and rotatably mounted in said bore, said shaft connected to said barrel and arranged to pivot therewith in the bore, and said barrel being arranged for axial movement to insure registration of said shaft with the slot in the first mentioned leg.

4. In an instrument, a pair of legs, one leg having a transverse cylindrical bore and having a slot communicating with the bore, a cylindrical barrel slidably and rotatably mounted in the transverse bore and having a diametrical bore of smaller diameter than the width of the slot and terminating in a countersink, a threaded shaft pivotally mounted on the other of said legs and extending through the diametrical bore and countersink and the slot in the first mentioned leg, a nut having an axial tapering extension and threaded on said shaft, the extension and slot in said leg being so arranged that the extension enters the countersink and frictionally holds the shaft and the cylindrical barrel together without binding on an edge of the slot in the leg.

THEODORE G. ALTENEDER.
